UNITED STATES PATENT OFFICE.

FRANK B. WOOD, OF NEW YORK, N. Y., ASSIGNOR, BY MESNE ASSIGNMENTS,
TO THE GAMEWELL FIRE ALARM TELEGRAPH COMPANY, OF SAME
PLACE.

AUTOMATIC ELECTRIC SIGNALING APPARATUS.

SPECIFICATION forming part of Letters Patent No. 275,006, dated April 3, 1883.

Application filed July 11, 1882. (No model.)

To all whom it may concern:

Be it known that I, FRANK B. WOOD, a citizen of the United States, and a resident of the city, county, and State of New York, have invented a new and useful System of Automatic Electric Signaling and Apparatus Therefor, of which the following is a specification.

My invention relates to that class of electric signaling systems employed in fire-alarm, district, and other similar municipal telegraphic organizations, which systems ordinarily comprise a principal or central station, and two or more auxiliary or sub-stations located at different points within the geographical district which the principal station is designed to serve. At each sub-station means are provided whereby a determinate arbitrary signal may be transmitted through an electric circuit to the principal station, by setting in action automatic machinery attached to a circuit-breaker or transmitter, which, while in motion, sends a predetermined stereotyped signal appropriated to and designating the particular station. The signal thus transmitted is received by an operator at the principal or central station upon suitable apparatus, actuated by an electro-magnet which responds to the electrical impulses from the sub-station. This electro-magnet may actuate a recording apparatus or register, and thus impress or mark the signals upon a moving strip of paper; or it may produce corresponding strokes upon a bell or gong; or both these methods may be used in conjunction, thus indicating to the attendant, either by the number of characters marked upon the paper or by the number of strokes upon the bell, the designating number of the station from whence the signal has been sent.

The object of my invention is to provide a system whereby, after the completion of the transmission of a predetermined signal through an electric circuit from a sub-station to the principal station, a signal of acknowledgment will be automatically returned in like manner to the sub-station, thereby notifying the sender that his signal has been duly received. This end I attain by setting in operation at the principal station, through the action of an

electro-magnet responding to the signals or impulses proceeding from the sub-station, automatic mechanism which produces an arbitrary signal of acknowledgment upon suitable receiving apparatus at the sub-station, immediately after the completion of the reception of the original signal at the principal station.

The invention also embraces certain details of mechanism and organization of electric circuits for producing the hereinbefore-mentioned results.

The subject-matter claimed as new will be hereinafter specifically designated.

The accompanying drawing is a vertical transverse section of a signal-box constituting the sub-station, and exhibiting the construction and arrangement of the automatic mechanism, in connection with which the apparatus at the principal station and the uniting electric circuits are illustrated in diagram.

In the drawing I have represented one principal or central station and three sub-stations, respectively designated as stations I, II, and III. I have shown the necessary apparatus for the automatic transmission of the station-signal and the reception of the return-signal at station II only, it being understood that the apparatus is precisely similar to this at sub-stations I and III except as to the particular construction or arrangement of the circuit breaking or transmitting wheel, which has a different signal stereotyped upon it at each sub-station, thus enabling the different station-signals to be readily distinguished one from another by the operator at the principal station, as hereinafter set forth.

The automatic transmitting apparatus at each sub-station preferably consists of a metallic circuit-breaking wheel, W, which is caused to revolve in one direction in a well-known manner by means of a train of wheel-work and a coiled spring, which, when a signal is to be transmitted, is wound up by means of a crank, C, and upon the crank being released by the hand of the operator the recoil of the spring acting through the train of wheel-work causes the transmitting-wheel W to perform one complete revolution in the direction indi-

cated by the arrow in the figure. In the periphery of the wheel W recesses or notches w' w^2 are formed, and these are arranged in systematic groups, so as to constitute a numerical signal. For example, in the wheel shown in the drawing the group w' consists of three notches, signifying numeral 3, and the group w^2 of four notches signifying numeral 4, the entire signal being 34. At w^3 an elongated notch or recess is cut from the periphery of the wheel W , of a length equal to about one-fourth of its entire circumference, the object of which arrangement will be hereinafter explained.

An insulated contact-spring, s' , is mounted upon a part of the frame supporting the above-described mechanism and presses firmly by its own resiliency against the periphery of the circuit breaking or transmitting wheel W , so as to form an electrical connection therewith as it revolves, except while one of the notches or spaces $w' w^2 w^3$ is passing beneath its extremity.

The apparatus at the principal station consists of an electro-magnet, M , which may be the same electro-magnet which is employed to actuate the recording or signaling apparatus, or may be an independent electro-magnet, as found most expedient in any particular case. The armature p of this electro-magnet is mounted upon a lever, P , at the opposite extremity of which is a detent, p' , which normally engages with a stop, q , and thereby holds in check a system of wheel-work propelled by a spring or weight, which, when released by the action of the electro-magnet M , will cause the axis v and its attached transmitting-wheel, hereinafter described, to make one complete revolution, after the completion of which it is again arrested by the stop q coming in contact with the detent p' . The axis v of the wheel-work at the principal station carries a circuit-breaking or circuit-changing metallic wheel, X , mounted rigidly thereupon, as shown in the figure. The wheel X has a certain determinate number of notches or recesses, preferably two, as shown at $x x$, cut at a certain point in its periphery, as shown in the figure, and a segment, X' , as shown in the figure, is mounted behind and concentric with the wheel X , being also in electrical connection therewith and with the frame of the mechanism also. Insulated contact-springs s^2 and s^4 are adjusted to press firmly against the uncut portions of the peripheries of the circuit-wheel and segment, respectively, as they revolve. When the apparatus is at rest the spring s^2 rests upon the wheel X , while the spring s^4 , although projecting into the path of the segment X' , is not normally in contact therewith. The notches or recesses $x x$ upon the wheel X serve to transmit the return or acknowledgment signal to the sub-station, where it is received upon a small bell or going, B , which is struck by a hammer, b , attached to the armature-lever n of an electro-magnet, m , said lever being pivoted at n' , and provided with a retracting-spring, n^2 .

It is essential to the proper action of the apparatus that the mechanism which causes the rotation of the shaft v and its attached circuit-wheel X at the principal station should revolve synchronously with that which causes the rotation of the transmitting-wheel W at the sub-station, so that they will perform their respective revolutions in equal times, or nearly so. This may be conveniently effected by attaching to the wheel-work of each apparatus a recoil-escapement, a vibrating bar, or other well-known means of producing synchronism between independent mechanical movements. The apparatus shown in the drawing is designed to be synchronized by means of a recoil-escapement, as therein indicated.

The operation of my improved apparatus is as follows: When the entire system is in its normal condition the transmitting-wheels at the principal station occupy the respective positions represented in the drawing. The electric circuit which unites the several sub-stations with the principal station may be traced as follows: commencing at the positive pole of the battery E , which battery is preferably located at the principal station, a constant current passes by the wire 1 to the signal-box at sub-station I, thence by wire 2 to the binding-screw y of the signal-box at station II, thence by wire 3 to contact-spring s' , which is in electrical connection with the transmitting-wheel W , upon the periphery of which it rests. The current therefore passes through the wheel W and through the frame of the signal-box upon which it is mounted, and thence to the attached binding-post z , thence by wire 4 to sub-station III, and thence through any required number of similar sub-stations in their order, after which it returns by wire 5 to the binding-screw 6, and thence by wire 7 to contact-spring s^2 , through circuit-wheel X and frame F of the mechanism to screw s^3 , and thence by wire 8 to the electro-magnet M , and thence by wire 9 to the negative pole of the battery E . Thus the electro-magnet M is normally traversed by a constant current, so that its armature-lever P holds the mechanism at the principal station in check by means of the stop q . If, now, a person at sub-station II wishes to signal the operator at the principal or central station, he sets the transmitting-wheel W in motion by pulling down the crank C , and thus winding up the coiled spring which impels said wheel. The wheel commences and completes one revolution in the direction indicated by the arrow and then stops, and as the several spaces or notches w' , w^2 , &c., upon its periphery successively pass beneath the contact-spring s' the circuit is automatically interrupted, and these interruptions by their duration and frequency indicate the designating number of the sub-station in a well-known manner. The signal is thus transmitted by the alternate breaking and closing of the circuit during the first three quarters of the revolution of the wheel W ; but during nearly the whole of the fourth quarter of the revolution

the circuit through the contact-spring s' is interrupted by the passage beneath it of the long space w^3 , which is cut from the periphery of the wheel, as hereinbefore explained. Behind the wheel W , and concentric therewith, is an attached segment W' , which is in electrical connection with the said wheel, and occupies a portion of the circumference of the circle a little greater than that occupied by the portion of the wheel W , which is cut away at w^3 .

The insulated contact-spring s^5 is so mounted as to project into the path of the segment W' , and hence when the transmitting-wheel W has completed three-fourths of a revolution 15 the contact-spring s^5 comes in contact with the segment W' just before contact is interrupted between the spring s' and the wheel W . The contact-spring s^5 is connected by a wire, 10, to the electro-magnet m , and thence to the binding-screw y . Hence it forms the terminal of a normally-open branch circuit, within which is included the electro-magnet m , the function of which is to sound the bell B . It will be understood therefore, from the above explanation, 20 that during the last quarter of the revolution of the transmitting-wheel W the main circuit traversing the signal-box is switched through the electro-magnet m and the segment W' , but is restored to its normal position just before 25 the completion of the revolution.

The arrangement of the electric circuits at the principal station is somewhat similar to that which has been described, there being provided a metallic segment, X' , which during the 30 last quarter of the revolution is in contact with the insulated spring s^4 . From the explanation hereinbefore given it will be understood that when the mechanism at the principal station is released, which release takes place instantly 35 upon the first interruption of the main circuit in transmitting a signal from the sub-station, the axis v and its attached circuit-wheel will perform its revolution synchronously with the wheel W at the transmitting or sub-station. 40 During the first three quarters of its revolution, while the signal is being transmitted from the sub-station, the contact-spring s^2 will rest upon the uncut portion of the periphery of the wheel X , and hence the circuit will remain un- 45 interrupted, and the signal will be properly received upon the electro-magnet M , and thereby transferred to the recording or sounding apparatus in the ordinary well-known way. During the last quarter of the revolution, how- 50 ever, the segment X' comes in contact with the contact-spring s^4 , and thereby closes a normally-open shunt-conductor, 11, which extends from the contact-spring s^4 to the point 12, thus, when closed, spanning the electro-magnet M 55 and also a small section of the battery E , and thereby preventing the demagnetization of the electro-magnet. During this latter portion of the revolution of the circuit-wheel X , and while the electro-magnet M is shunted or 60 bridged, the notches α pass beneath the contact-spring s^2 , thus interrupting the main cir- 65

cuit twice in succession and producing a corresponding signal upon the bell B at the sub-station by the action of the electro-magnet m , which is at the same time interposed in the 70 main circuit, as hereinbefore explained. It is obvious that this return or acknowledgment signal will not be produced at any other sub-station than the one from which the original signal proceeded, as the signal-operating electro-magnet m at each sub-station is only placed in circuit during the last quarter of the revolution of the transmitting-wheel after a signal 75 has been sent.

It will be readily understood, from the foregoing explanation, that in case the signal receiving or recording apparatus at the principal station should from any cause fail to respond to the signal transmitted from the sub-station the mechanism for transmitting the return 80 signal will either not be actuated at all or else not at the proper time, and hence no response will be received at the sub-station. The signalizer being thus made aware that his signal has not been received, may make use of some 85 other means for conveying the information desired.

Inasmuch as a very feeble electro-magnetic power is sufficient to actuate the bell B in the signal-box at the sub-station, a small and inexpensive electro-magnet, having but a few turns of wire in its coils, is preferably employed at m , for, as all the other magnets in the circuit are cut out at the moment when this one is required to be actuated, including the electro-magnet M at the central station, which is short-circuited with reference to the main line by the contact-spring s^4 and segment X' , I am thus enabled to make use of a powerful electro-magnet with many turns of wire in its coils 100 for actuating the signal-recording mechanism at the principal station without interfering in the least with the proper performance of the small magnet m at the sub station, which, although it is placed in the same circuit and actuated 105 by the same battery, is never operated at the same time.

I do not herein claim the combination, with an electric circuit uniting a principal station and a sub-station, of a register and transmitting wheel at the principal station, and a simultaneously-revolving transmitting-wheel, and mechanism for switching the circuit through an electro-magnet at the sub-station for the purpose of automatically announcing the 110 return-signal; nor the combination, with such an electric circuit, of a transmitter at the principal station for sending a return-signal, a relay-magnet, and a contact-segment for automatically cutting out the relay-magnet during a 115 portion of the revolution and afterward restoring it to the circuit; nor the specific means herein described for automatically cutting out and restoring the receiving-magnet from and to the said circuit, consisting of the combination of the revolving circuit wheel or wheels, 120 contact-springs, battery, and normally-open 125

shunt-circuit, as these several combinations are fully shown, described, and claimed in Letters Patent No. 252,353, granted to Henry J. Brower and myself as joint inventors, and 5 dated the 17th day of January, A. D. 1882, to which reference is had.

I claim as my invention—

1. The combination, substantially as herein-before set forth, of an electric circuit uniting a principal station with a sub-station, an automatic transmitter at the sub-station for transmitting a determinate signal through said circuit to the principal station, automatic mechanism at the principal station for producing a determinate signal at the sub-station, an electro-magnet for releasing or setting in action the last-named mechanism by an impulse proceeding from the transmitter at the sub-station immediately upon its initial movement, and 15 synchronously-moving mechanism at the two stations, whereby the respective signal-transmitting mechanisms are caused to perform and to complete their respective movements simultaneously.
2. The combination, substantially as herein-before set forth, of an electric circuit uniting a principal station with a sub-station, a normally-open branch of said circuit at the sub-station, an electro-magnet for actuating a signaling device 20 included in said branch at the sub-station, and synchronously-moving automatic mechanism for breaking and closing circuit at the principal and sub-stations, respectively, whereby said branch is automatically switched into the main circuit at the sub-station during the time in 25 which a return-signal is being automatically transmitted from the principal station.
3. The combination, substantially as herein-before set forth, of an electric circuit uniting a principal station with a sub-station, synchronously-moving automatic mechanism for breaking and closing the circuit at the principal and sub-stations, respectively, an electro-magnet for controlling the starting and stopping of 40 said automatic mechanism at the principal station, which electro-magnet is included in the said electric circuit at that station, a normally-open shunt spanning said electro-magnet, and a circuit-closer actuated by said automatic mechanism, which closes said shunt and thereby prevents said electro-magnet from responding during the time in which its associated mechanism is transmitting the return-signal to the sub-station.
4. The combination, substantially as herein-before set forth, of an electric circuit uniting a principal station with a sub-station, synchronously-moving automatic mechanism for transmitting signals by alternately breaking and closing said circuit at the principal and sub-stations, respectively, an electro-magnet at 55 each station for responding to the impulses proceeding from the automatic transmitter at the other station, and switching devices attached to each of said automatic transmitters, whereby the electro-magnet at each station is 60 prevented from responding during the time of transmission of a signal by its associated transmitter.
5. The combination, substantially as herein-before set forth, of an electric circuit uniting a principal station with a sub-station, automatic circuit-wheels at each of said stations moving synchronously with each other and organized, substantially as described, to transmit a determinate signal through said circuit during a definite but different portion of their respective revolutions, and receiving electro-magnets at each station responding to the signals automatically transmitted from the other 70 station.
6. The combination, substantially as herein-before set forth, of an electric circuit uniting a principal station with a sub-station, an electro-magnet at each of said stations, automatic 75 circuit-wheels at each of said stations moving synchronously with each other and so organized as to cause said circuit to traverse said respective electro-magnets during a determinate but different portion of their respective revolutions, and automatic transmitting devices upon said circuit-wheels organized, substantially as described, so as to be operated during that portion of their respective revolutions in which the associate electro-magnet is 80 not in the direct circuit.
7. The combination, substantially as herein-before set forth, of a circuit-wheel for transmitting determinate signals by alternately breaking and closing an electric circuit, a segment attached to and concentric with said circuit-wheel, and an independent or branch circuit which is closed through said segment during a determinate portion of its revolution while the main circuit is held open.
8. The combination, substantially as herein-before set forth, of an automatic circuit-wheel for transmitting determinate signals by alternately breaking and closing an electric circuit, a segment attached to said circuit-wheel for closing an independent or branch circuit during a determinate portion of its revolution while the main circuit is held open, and an electro-magnet for receiving signals included in said independent or branch circuit.
9. The combination, substantially as herein-before set forth, of an electric circuit uniting a principal station with a sub-station, automatic mechanism for transmitting signals by alternately breaking and closing said circuit situated at the principal and sub-stations, respectively, an electro-magnet of comparatively great electrical resistance at the principal station, and an electro-magnet of comparatively small resistance at the sub-station, each for responding to the impulses proceeding from the automatic transmitter at the other station.
10. The combination, substantially as herein-before set forth, of an electric circuit, an electro-magnet, an automatic circuit-wheel under control of said electro-magnet for transmitting

determinate signals by alternately breaking and closing said electric circuit, a segment attached to said circuit-wheel, a shunt-circuit spanning said electro-magnet, which is closed through said segment during a determinate portion of the revolution of the circuit-wheel, and an independent electro-magnet for receiving signals which responds to the impulses from the automatic circuit-wheel.

In testimony whereof I have hereunto subscribed my name this 8th day of July, A. D. 1882.
